STATIONARY INDUCTION APPARATUS

Ordean Kiltie, Fort Wayne, Ind., assignor to
 Ballastran Corporation, Fort Wayne, Ind., a
 corporation of Indiana

Application June 17, 1949, Serial No. 99,713

3 Claims. (Cl. 317—165)

1

This invention relates to stationary induction apparatus and is particularly directed to the core structure of a transformer having a deliberately introduced leakage path to provide for operation of a magnetically sensitive external device.

The primary object of the invention is to provide a core structure for an apparatus of the above character which shows greatly increased efficiency over known units of a similar nature.

Another object of the invention is to provide a core structure which is simple and efficient in operation, easy to assemble and which cannot become misadjusted after assembly.

Another object of the invention is to provide a core structure for an induction apparatus composed of a series of laminations of varying size and shape to direct the flux through the transformer into a particular path for increased effectiveness in the operation of an external magnetically sensitive device.

Other objects and advantages of the invention will become apparent from the following specification, reference being had to the accompanying drawings in which:

Fig. 1 is a circuit diagram showing a typical circuit in which the present invention is usable; Fig. 2 is a diagrammatic side elevation, with parts broken away, of a unit embodying the present invention; Fig. 3 is a bottom elevational view of the unit; and Figs. 4 and 5 are sections on lines 4—4 and 5—5, respectively of Fig. 2.

Referring to the drawings, and particularly to the circuit diagram of Fig. 1, the present invention is particularly directed to the core structure of a transformer diagrammatically indicated at T. The transformer is shown as being of the auto-transformer type although separate primary and secondary windings may be provided if desired, rather than the tapped single winding indicated. The transformer is associated with a power source 10 such as a battery having one side grounded and with a glow discharge lamp 11 in series with one winding of the transformer, the other winding being grounded. Power is applied to the center tap of the transformer in the usual manner through a switch 12 having a shunting capacitor 13 to reduce arcing at the switch points as the switch is opened and closed. In the device shown the ratio of turns in the transformer windings is such that discharge occurs in the lamp 11 from the power source 10 whenever switch 12 is opened and the flux in the core collapses.

As indicated in Fig. 2 the transformer is of the core type, and the core preferably comprises gen-

erally, a series of U-shaped laminations having the open leg closed by straight laminations designated 14. The transformer winding is disposed around one leg of the core and switch 12 is associated with another leg which will be presently described.

Switch 12 is preferably of the hermetically sealed type with the switch elements housed in a glass envelope, designated 15. One of the switch elements, designated 16, remains substantially stationary while the cooperating element 17 is drawn into and out of engagement with the stationary element as flux in the core rises and falls as hereinafter described. Element 17 is made of a magnetic material such as soft iron and is pivoted about the point where it is sealed in the glass envelope 15. The normal position of the element is as indicated in the drawing, in the closed position against contact 16. Element 17 is drawn out of position against its biasing spring force by any magnetic attraction operating in a direction perpendicular to the plane of the stationary contact.

By reason of its close association with the transformer core it will be seen that sufficient leakage flux from the core would draw movable contact 17 out of position and break the circuit between contacts 16 and 17. By the present invention such leakage flux is deliberately introduced in an improved manner and concentrated at the exact point where it is needed. The leakage flux can, of course, be caused by an air gap in those transformer laminations immediately adjacent the point of closest approach of contact 17 to the core. Since an air gap causes dispersion of the flux in all directions, where a concentration of the flux in paths which will include the movable switch arm 17 is desired, the present invention is directed to causing definite flux concentration. Thus the immediately adjacent outer core laminations are provided with a toothed form of air gap designated 18 having relatively wide side portions and more closely spaced center portions 19 facing each other. As indicated in Fig. 5 the teeth 19 are immediately adjacent the point of closest approach of the movable switch arm 17. Since flux across the air gap 18 will be principally concentrated in the teeth 19 a very large portion of the flux flowing in the laminations, of which the teeth are a part, will pass across the gap formed by the teeth and a portion of this flux will link the movable switch arm. Since the flux field tends always to contract, the arm is drawn in a direction toward the core and the contacts 16 and 17 are separated and the circuit with which they are associated opened.

2

If desired, the relative proportion of available flux in the core laminations normally including the air gap may be increased by introducing a larger air gap 20 in a few of the laminations immediately underlying the outer laminations which include the operating air gap 18 and teeth 19. The operation of the unit may also be varied by making the discontinuous laminations of a different magnetic reluctance than the continuous laminations indicated in Fig. 3. As there indicated, the continuous laminations, designated 21, may be made of a highly permeable material to increase the flux in the circuit while the discontinuous laminations including air gap 20 and operating air gap 18 may be made of a material of higher reluctance.

The time required for flux build-up is governed not only by the reluctance of the magnetic path, but may also be altered by the provision of a shorting or shading turn in the form of a copper or similar electrically-conducting non-magnetic strap 22 indicated principally in Fig. 4. The strap 22 may also be conveniently used to hold the switch envelope 15 in its proper physical relation to the core parts. The strap 22 may be adjusted lengthwise of the core and switch envelope and will, in some measure, affect the rapidity with which the flux rises and decays in the core and thus the periodicity of the flash of lamp 11.

In operation, once the circuit shown in Fig. 1 is established with switch 12 closed, current will flow through the transformer and flux in the core will build up. When the flux in the transformer core builds up, a certain proportion of it leaks through the gap 18 and is diverted outwardly to include the movable switch arm 17 in the magnetic circuit. When sufficient flux has been built up and so diverted, the contracting force of the magnetic field established thereby draws the movable contact 17 out of its position against the stationary contact 16 and opens the circuit. The rapid decay of flux causes the lamp to flash. When the flux has decayed to the point where the spring force of movable arm 17 can again return the arm to its circuit closing position, the circuit is reestablished and flux build-up in the core starts again in the next cycle. The lamp 11 thus flashes on and off and flashing will continue as long as the battery 10 is capable of furnishing sufficient energy to cause the discharge. Since the only waste energy in the system is the flux leakage out of the core and since such leakage is deliberately introduced, it is, of course, highly desirable that the leakage be confined to that portion of the core where it is needed for operation of magnetic switch arm 17.

While the invention has been disclosed in connection with a specific form and disposition of the part, it will be appreciated that certain modifications and changes may be made therein without departing from the scope of the appended claims.

What I claim is:

1. A stationary induction apparatus for the operation of an external unit having a flux responsive element movable in a fixed path, said apparatus comprising in combination, a stacked laminated closed core for establishing a magnetic circuit adjacent said external unit, said flux responsive element being positioned adjacent the broad face of an outermost core lamination, a flux leakage path in line and under said flux responsive element, said flux leakage path com-

prising a partial air gap in the outer laminations of the core nearest said flux responsive element, said outer laminations being continuous along their longitudinal edge portions, means for increasing the flux concentration under said flux responsive element, comprising a larger air gap in the intermediate laminations directly under said outer laminations and said flux responsive element, said intermediate laminations being completely discontinuous where they form said larger air gap.

2. A stationary induction apparatus for the operation of an external unit having a flux responsive element movable in a fixed path, said apparatus comprising in combination, a stacked laminated closed core for establishing a magnetic circuit adjacent said external unit, said flux responsive element being positioned adjacent the broad face of an outermost core lamination, a flux leakage path in line and under said flux responsive element, said flux leakage path comprising a partial air gap in the outer laminations of the core nearest said flux responsive element, said outer laminations being continuous along their longitudinal edge portions, means for increasing the flux concentration under said flux responsive element, comprising a larger air gap in the intermediate laminations directly under said outer laminations and said flux responsive element, said intermediate laminations being completely discontinuous where they form said larger air gap and means for mounting the external unit on said laminated core comprising an electric conducting non-magnetic strap disposed partially around said core and said external unit.

3. A stationary induction apparatus for the operation of an external unit having a flux responsive element movable in a fixed path, said apparatus comprising in combination, a stacked laminated closed core for establishing a magnetic circuit adjacent said external unit, said flux responsive element being positioned adjacent the broad face of an outermost core lamination, a flux leakage path in line and under said flux responsive element, said flux leakage path comprising a partial air gap in the outer laminations of the core nearest said flux responsive element, said outer laminations being continuous along their longitudinal edges, and having a large discontinuance in those portions adjacent said longitudinal edges and a smaller discontinuance in the central portion of said laminations, means for increasing the flux concentration under said flux responsive element comprising a much larger air gap in the intermediate laminations directly under said outer laminations and said flux responsive element, said intermediate laminations being completely discontinuous where they form said much larger air gap.
